Attorneys.

UNITED STATES PATENT OFFICE.

ANDRE VELUARD, OF PH^LADELPHIA, PENNSYLVANIA.

PILE-CUTTING DEVICE FOR USE IN LOOMS FOR WEAVING PILE FABRICS.

1,303,620.

Specification of Letters Patent. Patented May 13, 1919.

Application filed June 20, 1918. Serial No. 240,987.

To all whom it may concern:

Be it known that I, ANDRE VELUARD, a citizen of the United States, residing in the city of Philadelphia, State of Pennsylvania, have invented certain new and useful Improvements in Pile-Cutting Devices for Use in Looms for Weaving Pile Fabrics, of which the following is a full, clear, and exact description, reference being had to the accompanying drawings, forming a part of this specification.

My invention relates to improvements in pile cutting devices for use in looms for weaving pile fabrics wherein the pile is formed of floats of weft threads over pile wires which extend in the direction of the warp.

When it is desired to cut the pile of fabric woven on looms of this character, cutting devices are employed which are connected to and form continuations of the pile wires and to which the pile is fed as rapidly as the fabric is produced by the loom.

The object of my invention is to provide a pile cutting device of novel, simple and efficient construction adapted to be connected to a pile wire and to receive the pile therefrom and cut it as the fabric is advanced by the loom; and in which a support provided with a pile receiving part is employed in combination with a pivoted knife and movable means on the support, connected to the knife and adapted to be operated by mechanism of the loom to actuate the knife relatively to its support to effect the cutting operation by causing the cutting edge of the knife to sweep across the pile as it is advanced along the pile receiving part of the support.

With the above and related objects in view, my invented device consists of the elements and the combinations of them hereinafter described and claimed.

In the accompanying drawings, illustrating my invention,

Figure 1 is a view of a cutting device embodying my invention, as seen from one side

thereof, showing part of a loom in section, to which the device is applied.

Fig. 2 is a view of the device as seen from the opposite side thereof.

Fig. 3 is a plan view of the device.

Figs. 4 and 5 are transverse sections of the device, on lines 4-4 and 5-5, respectively, of Fig. 2.

Referring to the drawings, 2 designates the body portion of my improved cutting device. The body portion 2 constitutes the support for the other elements of the device and it is preferably made of sheet metal bent to form a downwardly facing top groove 3 and an upwardly facing bottom groove 6 connected at one side of the device by a side wall 7. Projecting rearwardly from one end of the bottom of the side wall 7 is a slender part 8, the rearward end of which is adapted to be connected to the forward end of a pile wire 9. The part 8 forms, in effect, a continuation of the pile wire 9, and it is adapted to receive the pile 10 therefrom as the fabric 11 is produced and advanced by the loom.

Projecting forwardly from the bottom of the side wall 7 is an arm 12 having a downwardly turned free end portion 13 by means of which the body portion or support may be secured to the loom frame. As herein illustrated the support 2 rests upon a plate 14 which is secured to and supported by a bar 15 which extends parallel to the breast beam 16 and which is secured to and supported by brackets 17 projecting fixedly from the breast beam 16. The support 2 is firmly held in a fixed position on the loom by a clamp bar 18 which is secured to the bar 15 by means of screws 19 and between which and the bar 15 the downwardly turned end 13 of the arm 12 is clamped.

The bottom groove 6 extends into the part 8 and arm 12, and extending into and between the grooves 3 and 6, and fitted to slide longitudinally therein, is a plate member 20. The member 20 has a rearwardly extending arm 21 provided with a laterally projecting pin 22 extending through a slot 23 formed

in a plate-like knife 24 which is held normally in engagement with the pin 22 by and between a head 25 thereon and the body of the arm 21. The knife 24 is arranged between an extension 26 of the side wall 7 on one side of the groove 6 and an extension 27 on the opposite side wall of the groove 6. The knife 24 is pivotally mounted on a pin 28 which penetrates the knife 24 and the wall extensions 26 and 27 on the respective sides thereof; and the knife 24 is provided with a sharp cutting edge 29 on a curved line concentric with the pivot pin 28. The cutting edge 29 is adapted to work above the pile-receiving part 8 and to sweep into and from the groove 6 in the part 8 when the knife 24 is reciprocated on the pivot pin 28; and the knife 24 is adapted to be thus reciprocated by the member 20 when it is moved back and forth within the grooves 3 and 6, and the pin 22 working in the slot 23 and effecting the reciprocations of the knife 24, when the member 20 is reciprocated.

The knife pivot pin 28 is carried by the free end of a spring arm 30 which extends from the inside of the wall 7 and which is secured thereto by rivets 31. The arm 30 normally holds the pin 28 projected through the walls 26 and 27 and the knife 24; and when it is desired to remove the knife 24 from the device, the arm 30 may be sprung outwardly to withdraw the pin 28 from the knife 24 to permit its removal. After the pin 28 has been withdrawn from the knife 24 it may be readily removed from between the walls 26 and 27 and withdrawn from the pin 22 for sharpening or other purposes. The member 20 is cut out, at 32, to receive one end of the spring arm 30 in the same plane therewith and to permit the reciprocations of the member 20 without interference with the arm 30.

The forward end of the member 20 extends beyond the wall 7 and has a notch 33 cut therein to receive a rib 34 on the bar 35 which is secured to a bar 36. The bars 35 and 36 and rib 34 extend parallel to the breast beam 16 and the ends of the bar 36 are supported by rollers 37 which rest upon brackets 38 projecting fixedly from the ends of the breast beam 16. The bars 35 and 36 are adapted to be moved toward and from the breast beam 16 by suitable mechanism of the loom to effect the back and forth movements of the member 20 for the reciprocation or actuation of the knife 24.

A plurality of the cutting devices hereinbefore described are adapted to be employed on a loom, the number employed corresponding with the number of rows of pile floats to be cut. The devices are arranged side by side on the bars 14 and held in place by the clamping bar 18, each device being connected to a pile wire 9 of the loom; and

the members 20 of the several devices are reciprocated to actuate the knives 24 thereof by the bar 35 which is common to all of them.

As the fabric is produced by the loom it is advanced over the breast beam 16 by the usual take-up roller, thereby drawing the pile from the wires 9 onto the pile receiving parts 8 of the cutting devices and along the parts 8 to the knives 24 where the pile is cut. After being cut, the pile moves down from the cutting devices on the respective sides thereof and moves with the fabric 11 across the forward face of the breast beam 16 to the usual take-up roller as rapidly as the fabric is produced.

80

I claim:

1. A pile cutting device comprising in combination a support having oppositely disposed grooves, an arm fixedly mounted in said support, a knife pivotally mounted on said arm, a member slidably movable in the grooves of said support, connecting actuating means between said slideable member and said knife adapted to rock the knife on its pivotal bearing to effect the cutting operation, and means forming part of said support adapted to direct the pile to the cutting edge of the knife.

85

2. In a pile fabric cutting device, the combination of a support having grooves therein, a knife pivoted on the support, and a member slidably fitted to the grooves of the support and connected to and operative to actuate the knife to effect the cutting operation, the support having a part adapted to receive the pile and direct it to the cutting edge of the knife.

95

3. In a pile fabric cutting device, the combination of a support, a knife, and a spring arm carried by the support and having a pivot pin penetrating the knife and pivotally supporting the same, said arm being movable relatively to the knife to withdraw the pivot pin therefrom, the support having a part adapted to receive the pile and direct it to the cutting edge of the knife, the said knife being movable on its pivot to effect the cutting operation.

105

4. In a pile fabric cutting device, the combination of a support, a knife pivoted thereon and having a slot therein, a spring arm carried by the support and having a pivot pin penetrating the knife and pivotally supporting the same, said arm being movable relatively to the knife to withdraw the pivot pin therefrom, and a member movable on the support and having a pin projecting into said slot and operative to actuate the knife to effect the cutting operation, the support having a part adapted to receive the pile and direct it to the cutting edge of the knife.

110

5. In a pile fabric cutting device, the com-

120

bination of a support, a knife, and a spring
arm carried by the support and having a
pivot pin penetrating the knife and a part
of the support and pivotally supporting the
5 knife, said arm being movable relatively to
the knife to withdraw the pivot pin there-
from, the support having a part adapted
to receive the pile and direct it to the cut-
ting edge of the knife, the said knife being
movable on its pivot to effect the cutting 10
operation.

In testimony whereof, I affix my signa-
ture hereto.

ANDRE VELUARD.
